MOLECULAR STORAGE OF INFORMATION

Robert H. Dicke, 37 Jefferson Road, Princeton, N.J.

Filed Mar. 12, 1956, Ser. No. 570,911

7 Claims. (Cl. 340—173)

This invention relates to molecular or atomic memory systems and it has for its object to provide a novel and improved method and means for storing information in the form of microwave energy.

Another object of the invention is to provide a novel and improved system employing a microwave resonance to store information in a series of pulses, and for recalling such information after a desired delay time by the application of a recall pulse.

Another object is to provide a molecular or atomic memory system employing a microwave resonant gas to store information in the form of microwave pulses at the resonance frequency of said gas.

Various other objects and advantages will be apparent as the nature of the invention is more fully disclosed.

The various objects of the present invention are achieved by utilizing a molecular microwave system in which a microwave resonance phenomenon is employed to store information in the form of a series of pulses. The function is similar to that of a delay line except that the storage time (i.e. delay time) is variable, since the information is read out by applying a recall pulse to the device.

In carrying out the invention, the atoms or molecules of the particular microwave resonance medium or gas employed for storage purposes, such as ammonia, are contained in a long waveguide type cell or chamber excited in a mode for which the microwave travels as a plane wave down the cell. The atoms or molecules in the cell are initially in a condition of thermal equilibrium. Information is fed into the gas in a series of weak pulses at the resonance frequency of the gas. Thereafter, on feeding in a "recollection" pulse as hereinafter described, the gas proceeds to radiate the information previously stored.

In one embodiment of the invention the stored information is recalled by one or more "recollection" pulses, i.e. a microwave pulse of such strength that the atoms or molecules are excited from one of the two energy states of the gas to the other. Upon feeding in one recollection pulse, the gas radiates the information as a series of pulses in the reverse order, but by employing a double time separated pulse the recalled memory pulses may be made to come out in the same order as they went in. In another embodiment of the invention the gas is first prepared for the reception of information pulses by the application of a preliminary pulse which initiates the information input period. This preliminary pulse is a pulse of such strength that the individual molecules are thrown from a state of definite energy into a superposition state in which they are partly and with equal probability in each of two energy states defining the resonance frequency. The preliminary pulse is followed by a series of weak information pulses, and by a storage interval during which the gas is not excited. The storage interval is followed by another pulse similar to the preliminary

2

pulse which serves as a recall pulse, causing the gas to radiate back the stored information.

The invention is described more in detail in connection with the accompanying drawing, in which:

5 Fig. 1 is a schematic diagram, partly in block form, of a molecular or atomic memory system embodying the invention;

10 Fig. 2 is a diagrammatic perspective view of a waveguide type storage cell for use in the system of Fig. 1;

15 Figs. 3a and 3b are diagrams used in describing the operation of the system pursuant to one embodiment of the invention; and

20 Fig. 4 is a diagram used in describing the operation of the system pursuant to another embodiment of the invention.

25 Similar reference characters are applied to similar elements throughout the drawing.

In the drawing, Fig. 1 shows a source 1 of weak microwave information pulses to be stored, directly

30 coupled to the input end of a waveguide type cell or chamber 2 by means of a section of rectangular hollow-pipe waveguide 3. The structure of the cell 2 will be

35 described later with particular reference to Fig. 2. The output end of the cell 2 is coupled to a further waveguide section 4. The cell 2 is made gas-tight by a pair of microwave permeable windows 5 and 6 formed of a

40 material such as quartz or mica. One of said windows 5 is positioned in the waveguide section 3 near the input end of cell 2 while the other window 6 is positioned in

45 waveguide section 4 near the output end of cell 2. A source 7 of recollection pulses is coupled to the waveguide section 3 via another section of absorptively terminated rectangular waveguide 8 and a directional coupler 9.

50 The cell 2 contains a gas at low pressure capable of exhibiting molecular resonance. The gas normally presents positive attenuation to microwave energy and selectively absorbs microwave energy at frequencies at which the gas is resonant. Such gases are numerous and include, by way of example, ammonia, carbonyl sulfide, and the methyl halides. In the present instance it is assumed that the chosen microwave resonant gas is ammonia the pressure of which is made low enough so that the molecules are thermally relaxed by wall collision.

55 Fig. 2 shows a waveguide cell or chamber 2 which may be employed in the system of Fig. 1. The said cell comprises a long section of rectangular hollowpipe waveguide having dielectric slabs 11 and 12 each of which is in contact with one narrow side wall of the cell and extends along its longitudinal axis, to slow the wave down

60 to $\lambda_g = \lambda$, for which the wave is a plane wave.

65 The cell 2 contains a series of septa 13, which may comprise a plurality of fine wires such as tungsten mounted on suitable metallic supports or frames 14, extending along the longitudinal axis of the cell. A convenient method of mounting is to seat the metallic sides of the septa frames 14 in longitudinal slots 15 in the dielectric slabs 11 and 12, as illustrated in Fig. 2. The septa 13 are electrically charged, as by a source of potential 16 through potentiometer 17, to a series of potentials to detune the gas molecules in the cell.

70 In the operation of the system described above the memory time is given by the time required for the molecules to reach walls in the cell 2. With a large waveguide cell with mode damping this may be as long as 50 μ sec., with a small cell 10 μ sec. The wider the range of tuning of the gas molecules, the more information storage capacity will be obtainable. Assuming a band width of 10 mc., information can be fed into the cell 2 at the rate of 10 pulses/ μ sec. and each pulse can have a variety of strengths. If the band is made wider, the pulse rate can be higher but the signal is weaker.

Information from the source 1 is fed into the gas in cell 2 in a series of weak pulses at the resonance frequency of the gas. In the diagram of Fig. 3 these pulses are represented as A, B, C and D. After the information pulses are fed in, a recollection pulse from source 7 is fed in, the recollection pulse being a microwave pulse of such a strength as to excite the gas atoms or molecules from one (the lower) of the two energy states which define the resonance frequency of the gas to the other (the higher) energy state. The gas then proceeds to radiate the information as a series of pulses in the reverse order D, C, B, A, as indicated in Fig. 3. However, by employing a double time-separated recollection pulse as indicated in Fig. 3, the memory pulses are made to come out in the same order in which they went in.

Another different mode of operation will now be described with reference to Fig. 4. The gas is first prepared for the reception of information pulses by a pulse S which initiates the information input period. The pulse S is a pulse of such strength that the molecule is thrown from a state of definite energy into a superposition state in which it is partly and with equal probability in each of two energy states. This initial pulse is followed by a series of weak information pulses such as A, B, C in Fig. 4, whose spacing and/or strength and phase is a source of information. The information input interval is followed by a storage interval during which the gas is not excited. This is in turn followed by another pulse R (like the pulse S) which serves as a recall pulse after which the gas radiates back the information stored.

The theory of operation is believed to be as follows: the molecules may be divided into classes of different resonance frequencies because of the doppler effect and/or perturbing static fields. The initial pulse S puts all molecules in a superposition energy state such that the probability of finding a molecule in the upper energy state equals the probability of finding it in the lower energy state. The subsequent train of information pulses A, B, C selectively excites molecules of a given class (i.e. those of a given definite resonance frequency) by an amount proportional to the amplitude of the cosine transform of the corresponding frequency. (Here the time origin is taken as the time of the first pulse S.) The probability of being in the upper energy state may be increased or decreased depending on the sine of this Fourier component.

After the initial pulse S followed by the train of information pulses, the cosine spectral distribution of the information pulse is written into the gas as a distribution in internal temperature over the classes of various resonance frequencies. The information as to the sine transform is carried in the changes in internal phases of the atoms. Remarkably enough it is possible to completely destroy these phases by making them random after the information pulses have been applied to the gas without any real loss in information stored. The information is completely contained in either the cosine transform or the sine transform. The reason for this is that the information is all contained in a time interval $t > 0$, measuring time t after the initial pulse S, and the sine and cosine transforms are directly connected. Consequently, there is no necessity for carefully controlling static fields to accurately preserve interval molecular phases. The internal temperature is independent of such fields. This allows a longer storage time and it may be possible to get storage times in excess of 100 μ sec.

The effect of the second (recall) pulse R may be described as follows: because of the distribution in internal temperature as a function of resonance frequency of the gas, the absorption coefficient of the gas is a complex function of frequency. Thus, because of the Kramers-Kronig relation between real and imaginary parts of the dielectric constant, the dispersion properties of the gas are uniquely given by the absorption spectrum. The Kramers-Kronig relation is set forth at page 343 of

Microwave Spectroscopy by Townes and Schawlaw (McGraw-Hill, 1955). If the gas is excited by a pulse it continues to radiate afterward because of the frequency dependence of the dielectric constant of the gas. This is just such as to cause the gas to radiate back the information pulse stored originally.

Thus, by employing the pulses S and R in the manner specified, instead of the pulses previously described which excite the atoms or molecules from one or two of the energy states to the gas, it is possible to store the information in the frequency dependence of the dielectric constant of the gas. Thus the internal phases of molecular states are not required and the conditions on uniformity of static fields is much less severe.

15 5 What is claimed is:

1. Information storage apparatus comprising a gas chamber, a microwave resonant gaseous medium confined within said chamber, the gas molecules of said medium having electric dipole moments and being convertible by microwave energy from a microwave attenuative state to a microwave radiant state, a source of microwave pulses containing the information to be stored, said pulses being of a frequency which is a resonant frequency of said medium for impressing said information on said medium in its attenuative state, a source of recollection pulses of microwave energy at a resonant frequency of said medium for inducing the occurrence of energy level transitions between energy levels of said medium thereby converting said medium from said attenuative state to said radiant state, coupling means connecting both of said sources to said chamber, and means for applying said recollection pulses to said medium at the conclusion of the desired storage time interval to recall said stored information.

time interval at least as long as the time interval required for the application of said information pulses to said medium.

7. Apparatus according to claim 1 wherein said attenuative state is a state of thermal equilibrium and including means for applying to said medium, preceding the application of said information pulses, a preliminary conditioning pulse to cause the individual molecules of

said medium to assume said two energy levels simultaneously with equal probability of being in either level.
